UNITED STATES PATENT OFFICE.

HAMILTON MICHELSSEN, OF MIAMI, FLORIDA.

SHIPPING CRATE.

Application filed August 17, 1922. Serial No. 582,336.

To all whom it may concern:

Be it known that I, HAMILTON MICHELSSEN, a citizen of the United States, residing at Miami, in the county of Dade and State of Florida, have invented certain new and useful Improvements in Shipping Crates, of which the following is a specification.

In the use of a shipping crate constructed in accordance with Letters Patent of the 10 United States No. 1,380,947, granted to me under date of February 17, 1920, it has been found that in re-icing, the operator will crown the ice in the center of the ice chamber and will then force the cover into closed 15 position. This filling of the ice chamber with an excess of ice and the forcible closing of the cover causes a sagging of the ice chamber floor until it touches and often bears with considerable pressure on the sheet 20 of insulation therebelow and on the fruit. This pressure often bruises and injures the fruit, and the sagging causes the water from the melted ice to collect and seep through the ice chamber floor onto the fruit, further 25 injuring the same and often rendering it unfit for sale on arriving at its point of destination, resulting in considerable loss to both the shipper and retailer.

The object of this invention is to provide a 30 bottom or floor for the ice chamber, which is effectively braced and supported to prevent the same from sagging in the center, and one constructed in such a manner as to enable a portion of the contents of the crate 35 to be used and the remainder to be maintained cool under the ice temperature.

With the above mentioned and other objects in view, the invention consists in the novel construction and combination of parts 40 hereinafter described, illustrated in the accompanying drawings and pointed out in the claim hereto appended; it being understood that various changes in the form, proportion, size and minor details of construction within the scope of the claim may 45 be resorted to without departing from the spirit or sacrificing any of the advantages of the invention.

To more clearly comprehend the invention, reference is directed to the accompanying drawings, wherein—

Fig. 1 is a longitudinal sectional view of the preferred embodiment of my invention.

55 Fig. 2 is a view in broken top plan of the preferred embodiment.

Fig. 3 is a like view, of a modified form of construction.

In the drawings 1 indicates a shipping container, preferably of wood, oblong in 60 plan, adapted to be closed by a hinged cover 2, maintained in closed position during transportation by a lock or other securing means 3.

The container is divided transversely by 65 the vertically extending wall 4, the upper edge 5 of which falls short of contacting with the under surface of the cover 2, and said wall divides the container into compartments 5' and 6 adapted for receiving the 70 avocados.

The container is divided, adjacent its upper surface, by the longitudinally disposed horizontal partition pieces 7, which provide the respective ice chambers 8 and 9 75 above the fruit receiving compartments 5' and 6. The partition pieces 7 are removably held in position by the rails or cleats 10, and the water resulting from the melting of the ice in the respective compartments 8 and 9 80 escapes therethrough through the weep openings 11. An air chamber 12 is provided between the partition pieces 7 and the upper surface of the fruit and the chambers 5' and 6 by a layer of cellular material 13 horizontally disposed longitudinally of the receptacle 1 beneath the pieces 7. This layer of cellular material maintains the excessive cold from the fruit contained within the chambers 5' and 6, and prevents the same from 90 becoming frosted.

It will be observed that the respective chambers 5' and 6; partition pieces 7 and the layer of cellular material 13 are independently removable, thus enabling the fruit 95 in one chamber to be removed while that in the other is maintained under a cooling temperature by a replenishment of the ice. The partition pieces 4, it will be observed, prevent the crowning of the ice centrally of the ice shipping crate, and provides a support for the inner edge of the wall 7. This breaking of the wall 7 and supporting the same midway of its length adds strength thereto and prevents its sagging, which was 100 the case in the shipping containers manufactured under the patent above mentioned.

Fig. 3 illustrates a container employing two vertically disposed partition pieces arranged at right angles to each other, one 110 transversely of the shipping container and the other longitudinally, thus dividing the

container into quarter sections, and it is to be understood that each of these sections is provided with its individual layer of cellular material and horizontally disposed 5 partition piece.

I claim:—

A refrigerator shipping crate for the transportation of fruit, comprising a box having its interior divided into a fruit receiving compartment and a superimposed ice receiving compartment, a removable horizontally disposed partition piece separating the said compartments and forming a bottom for the ice receiving compartment, 10 a vertical partition piece within the fruit receiving compartment for dividing the same vertically into a plurality of compartments 15 and on which said removable partition piece

rests, said partition piece dividing said ice receiving compartment vertically into a plurality of compartments, a layer of cellular material horizontally supported below the said bottom to provide an air space between said bottom and the fruit within the receptacle, and partly supported by said vertical partition piece, and to overlie the fruit within the fruit compartment to maintain the same from contacting with the undersurface of the bottom, weep openings formed in the walls of the ice compartment for the escape 25 of the water therefrom, a cover for the ice compartment, and means for locking the cover to the crate. 20

In testimony whereof I have signed my name to this specification.

HAMILTON MICHELSSEN.
